UNITED STATES PATENT OFFICE.

GERALD W. SKILBECK, OF KENOSHA, WISCONSIN.

ADJUSTABLE KEEPER.

1,357,084.

Specification of Letters Patent. Patented Oct. 26, 1920.

Application filed December 26, 1919. Serial No. 347,330.

To all whom it may concern:

Be it known that I, GERALD W. SKILBECK, a citizen of the United States, and resident of Kenosha, in the county of Kenosha and 5 State of Wisconsin, have invented new and useful Improvements in Adjustable Keepers, of which the following is a description, reference being had to the accompanying drawings, which are a part of this specification.

10 The present invention relates to certain new and useful improvements in latch keepers and refers more particularly to the latch retaining plate especially adapted for use on automobile doors.

15 In the automobile coupés or sedans now in general use, the latch strike face becomes worn after the car has run about two thousand miles and the keeper must then be removed and a new one employed or else more 20 metal must be added to the latch strike face thereof by welding or the like. If this is not done the doors rattle and cause considerable inconvenience to the operator and occupants of the car.

25 With the above and other objections in mind my invention has for one of its objects to provide a door latch keeper having an adjustable striking surface whereby the same may be readily adjusted to take up the wear 30 without the necessity of removing the keeper.

A further object of this invention is to provide a keeper of the class described which will not detract from the general appearance of the car and which by reason of its simplicity of construction will be capable of 35 comparatively cheap production.

With the above and other objects in view which will appear as the description proceeds my invention resides in the novel construction, combination and arrangement of 40 parts substantially as hereinafter described and more particularly defined by the appended claims, it being understood that such changes in the precise embodiment of the 45 herein disclosed invention may be made as come within the scope of the claims.

In the accompanying drawing I have illustrated two complete examples of the physical embodiment of my invention constructed according to the best modes I have so far devised for the practical application 50 of the principles thereof, and in which:

Figure 1 is a perspective view of a portion of a vehicle body and door illustrating my 55 invention as applied thereto.

Fig. 2 is a perspective view of my im-

proved adjustable keeper; parts being broken away and in section to more clearly illustrate the structural details thereof.

Fig. 3 is a view similar to Fig. 2 of a 60 slightly modified form of my invention.

Fig. 4 is a fragmentary sectional view taken on the line 4-4 of Fig. 2, and

Fig. 5 is a fragmentary sectional view taken on the line 5-5 of Fig. 3. 65

Referring now more particularly to the accompanying drawing, 10 designates a body portion of a vehicle body having an opening therein closed by a door 11 having concealed therein a lock including an operating handle 70 12 and a latch member 13 adapted to engage a latch keeper or retaining member 14 secured to the vehicle body as depicted in Fig. 1.

The latch keeper comprises a securing 75 plate 15 provided with securing screw receiving openings 16 and having a pair of complementary cam blocks or latch engaging segments 17 and 18 having the outer faces of their thick ends 19 providing a 80 latch strike face behind which the latch 13 engages. The block 17 is a primary lock as in case the door 11 is not closed tight enough to engage the latch 13 behind the block 18 the same will engage behind the 85 block 17 and thus prevent the door from swinging open, and my invention has to do only with the block 18 of the stop.

The end 19 of the block 18 wears down after the car has been used for several thousand miles and therefore permits the door to rattle and I provide means for taking up 90 this wear which consists of threaded stud members 20 disposed within threaded apertures 21 within the block 18 and having 95 their outer ends 22 projected outwardly of the end 19 of said block.

In this arrangement the ends 22 of the studs 20 provide a latch striking surface and as the ends become worn the same may be 100 readily adjusted by inserting a screw driver or other instrument into the rear of openings 21 to turn the studs to project their ends outwardly from the face 19.

In that form of my invention depicted in 105 Figs. 3 and 5 the detachable block or plate 23 is provided to take the place of the end 19 of the block 18 depicted in Figs. 2 and 4 and this plate is secured to the block 18 by means of cap screws or the like 24 having 110 their heads 25 recessed within counter-sunk openings 26 within said plate and having

their threaded ends engaged in threaded openings 27 within the block 18. The wear, on the outer face of the plate 23 is taken up by placing shims or washers 28 between 5 the plate 23 and the outer face of the block 18.

What I claim as my invention is:

1. A device of the class described comprising a keeper block having a striking 10 face, and a strike member disposed within said block and having a strike surface of less area than the striking face of the block, said member being movable into and out of the block to vary the relative positions of the 15 striking face of the block and the strike surface of said member.

2. A device of the class described comprising a keeper block having a striking face and provided with a longitudinally extending threaded bore communicating with the striking face, and a strike member having a threaded shank portion engaged in

said threaded bore and carrying a part having a strike surface, the threaded shank portion of said member being movable into and 25 out of the threaded bore to vary the relative positions of the striking face and the strike surface.

3. A device of the class described comprising a keeper block having a striking face 30 and provided with two longitudinally extending parallel threaded bores communicating with the striking face, and two exteriorly threaded strike members engaged within the threaded bores and having their outer ends projected beyond the striking face of said block to provide a strike surface, said strike members being movable into and out of said block to vary the relative positions of the striking face of the 40 block and the strike surface formed by the outer ends of said strike members.

In testimony whereof I affix my signature.

GERALD W. SKILBECK.
